UNITED STATES PATENT OFFICE.

FRANK E. FOSTER, OF SAPULPA, OKLAHOMA.

DERRICK-BRACING MEANS.

937,299.

Specification of Letters Patent. Patented Oct. 19, 1909.

Application filed March 27, 1909. Serial No. 486,207.

To all whom it may concern:

Be it known that I, FRANK E. FOSTER, a citizen of the United States, residing at Sapulpa, in the county of Creek and State 5 of Oklahoma, have invented certain new and useful Improvements in Derrick-Bracing Means, of which the following is a specification.

Out in the western portion of our country 10 thousands of oil derricks are blown down yearly by the high winds which sweep across the country. Various means have been employed in order to brace derrick structures of this type, such means being more or less 15 simple, but up to the present time no devices used have been practical or sufficient for the desired purpose.

The present invention consists of extremely simple bracing means which can be 20 readily applied to derricks which are commonly in use, and which is efficient for preventing the breaking in half and blowing down of derricks by the high winds before referred to.

25 The invention consists primarily in peculiar anchoring devices secured to the frame work of the derrick in such a way as to effectively brace and support the latter.

For a full understanding of the invention, 30 reference is to be had to the following detail description and to the accompanying drawings, in which—

Figure 1 is a perspective view of an ordinary form of oil derrick showing the invention applied thereto, certain crossed braces of the frame-work of the derrick being omitted; Fig. 2 is a fragmentary vertical sectional view showing more clearly just how the longitudinal bracing cables contact 40 with the braces and frame-work of the derrick construction, and Fig. 3 is a transverse section bringing out the arrangement of the bracing cables more clearly.

Throughout the following detail description 45 and on the several figures of the drawings similar parts are referred to by like reference characters.

Particularly describing the invention and referring especially to the illustration there- 50 in the drawings, the letter A designates the derrick proper, and the letter B the top portion thereof. The derrick comprises the ordinary construction and arrangement of parts including the corner post 1 and the 55 diagonal braces 2 which are located at inter-

vals in the frame work of the derrick and between the horizontal bars that connect the corner posts in the customary way.

The bracing means included within the invention consists of vertical cables design- 60 ated 3 one or more of said cables being located at each side of the derrick, and being peculiarly arranged and connected with the top of the derrick, and anchoring means at the base thereof. A hook 4 having an eye 4^a attached to the upper end of the cable 3 is adapted to engage over the top of the derrick and secure the cable thereto at this portion of the structure. At its lower end the cable 3 is secured to an eye 70 of a screw rod 6 which forms a part of the turnbuckle device 5. The other screw rod 7 of the turnbuckle device has an eye at the lower end adapted to engage with a hook 8 which is secured in any substantial way 75 to a sill or anchor 9 at the base of the derrick. The provision of the turnbuckle device 5 enables the owner of the derrick to properly adjust the tension of the cable 3 for most effective reinforcement of the derrick. 80

There being one of the bracing cables located at each side of the derrick it will be observed that the structure is reinforced, braced, or anchored from all sides against winds blowing from any direction. An es- 85 sential feature of the invention resides in the peculiar arrangement of the cables whereby the same contact with the braces 2 at the sides of the derrick and all the way down the structure. Contacting relation of 90 the bracing cables 3 with the braces 2 is secured by a proper arrangement of the anchors or sills 9 with which the cables are connected at their lower ends. It has been found that the bracing cables arranged in 95 the peculiar manner before described, are far more effective than guy wires connected with the derrick in the usual way, and hence the desirability of the present invention over prior devices for the same purpose. 100

Having thus described the invention, what is claimed as new, is:

In combination, a derrick embodying corner posts and horizontal braces connecting said posts together, and bracing means including a plurality of vertical cables arranged vertically with reference to the derrick, a cable being located between each pair of corner posts and in approxi- 105 mately parallel relation thereto, the said 110

cables being in contact with the horizontal braces, anchoring members located beneath the derrick and adjacent to each side thereof, turn buckle connections between said anchoring members and the cables adjacent thereto, and members detachably connecting the upper ends of the cables with the head or top portion of the derrick.

In testimony whereof I affix my signature in presence of two witnesses.

FRANK E. FOSTER.
